UNITED STATES PATENT OFFICE.

SIMEON J. FORD, OF PLACERVILLE, CAL., ASSIGNOR OF ONE-HALF TO BEN JAMIN G. PARLOW AND AMON MELTON, BOTH OF SAME PLACE.

CAR-COUPING.

SPECIFICATION forming part of Letters Patent No. 352,744, dated November 16, 1886.

Application filed August 25, 1886. Serial No. 211,851. (No model.)

To all whom it may concern:

Be it known that I, SIMEON JASPER FORD, of Placerville, El Dorado county, State of California, have invented an Improvement in Car-Couplings; and I hereby declare the following to be a full, clear, and exact description of the same.

My invention relates to that class of car-couplings in which a pivoted gravity-latch sustains the coupling-pin until forced back by the entering link, whereupon it releases the pin, so that it drops through the link, and thus couples the cars.

My invention consists in an apertured gravity-latch plate pivoted in the upper front portion of the draw-head chamber and hanging down at a backward inclination within said chamber, said plate supporting the coupling-pin upon the edge of its aperture and adapted to relieve it when raised by the entering link.

It consists, further, in connection with this gravity-latch, of a loose plate above and resting upon the latch-plate, and also apertured for the passage of the pin, said loose plate serving to more effectively cramp or bind the pin by its weight, and also to hold the link horizontal, as I shall hereinafter fully describe.

The object of my invention is to provide a simple and effective automatic car-coupling, which will avoid the necessity of the brakeman going between the cars to couple them.

Referring to the accompanying drawings for a more complete explanation of my invention, Figure 1 is a longitudinal vertical section of the draw-head, the pin and link being in elevation. Fig. 2 is a horizontal section of the draw-head, showing the plan of latch-plate D, the loose plate being removed. Fig. 3 is a front view of the draw-head, showing the depression a^2 . Fig. 4 is a horizontal section showing the plates D E in plan.

A is the draw-head, to be secured to the car in the usual manner, and having the chamber a , the rear wall, a' , of which is curved. The upper and lower walls of the chamber are perforated for the passage of the coupling-pin B when it engages the coupling-link C.

D is the latch-plate, which fits within the draw-head chamber, its upper end being pivoted in suitable manner in the upper front portion of the said chamber.

The latch-plate hangs downward at a backward inclination, and is stopped by a small lug or pin, d , in the side walls of the chamber. It has a hole, d' , made in it, which, when the plate is at rest, is not exactly in line with the pin-holes in the chamber, so that the pin cannot pass through it when the latch is hanging down in its normal position, but may when the latch-plate is raised, its hole then coming in line with the holes in the chamber. The coupling-pin B is thus supported by the hanging latch-plate until the link Centers, and by lifting up the plate allows the pin to drop through it, and thus effects the coupling. I have found that the cramping of the pin by the latch-plate alone is not as certain as is desired to prevent the pin from dropping by reason of a jar or shake, and therefore in order to make the device effective I use a second plate, E. This plate is entirely loose, not being connected in any manner with the rest of the coupling. It rests upon the top of the latch-plate D, and has its rear end curved to fit the rear wall of the chamber a . It is perforated by a beveled hole, e , which, when the plate is in a normal position, is not in line precisely with the hole in the plate D. The pin B passes through the loose plate E and rests upon the edge of the hole in the latch-plate. The loose plate E presses down by its own weight upon the pin and holds or binds it in position, so that said pin is forced against its seat or edge of the hole d' , in which it rests, and is less liable to be shaken from it by a jar. The plate E also adds weight to the latch-plate, whereby the link is held in a horizontal position by the weight of the two plates.

In the front of the floor of the draw-head chamber are the depressions or notches a^2 , in which the sides of the link C rest, to prevent it from turning to either side as it enters the opposing draw-head.

The operation of the car coupling is as follows: The pin B is held in an elevated position by resting upon the edge of the hole d' in the latch-plate D, and is held in this position by the weight of the loose plate E, which bears down upon it and perfectly cramps it. The link C enters the draw-head, and, coming in contact with the latch-plate D, raises it, and with it the loose plate E, the inner end of

which, bearing against the curved rear wall of the draw-head chamber, is forced up to relieve the pin, so that now, all the holes being in line, the pin drops through the link and the 5 coupling is complete.

Having thus described my invention, what I claim as new, and desire to secure by Letters Patent, is—

1. In a car-coupling, the pivoted gravity-10 latch plate D, resting at an inclination within the draw-head chamber and having a hole, on the edge of which the coupling-pin is supported, in combination with the loose plate E upon the plate D, and having an aperture 15 through which the pin passes, said plate E holding the pin to its seat in the latch-plate, substantially as herein described.

2. In a car-coupling, the draw-head A, the coupling-pin B, and the link C, in combination 20 with the inclined gravity-latch plate D, pivoted in the chamber and having an aperture supporting the pin on its edge, and the loose plate E, resting upon the plate D and holding the pin B to its seat in the apertured 25 latch-plate, substantially as herein described.

3. In a car-coupling, the draw-head A, having a chamber, a, with a curved rear wall, the

coupling-pin B, passing through the draw-head, and the link C, in combination with the inclined gravity-latch plate D, pivoted in chamber a and having the hole d', on the edge of which the pin is supported, and the loose plate E, resting upon the plate D and binding the pin in its seat in the latch-plate, said loose plate having a curved rear end coming in contact with the rear wall of the chamber a, whereby it is forced to relieve the pin when the plates are raised by the entering link, substantially as herein described. 30

4. An improved car-coupling comprising 40 the draw-head A, having the depression or notches a', the coupling-link C, resting in said notches, the rearwardly-inclined gravity-latch plate D, pivoted in the front portion of said draw-head and having the hole d', and a perforated loose plate seated upon the latch-plate and binding against the coupling-pin, substantially as herein described. 45

In witness whereof I have hereunto set my hand.

SIMEON J. FORD.
